(57) **CLAIM**

The ornamental design for a handbag lock, as shown and described.

DESCRIPTION

FIG. 1 is a front right perspective view of a handbag lock showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a reduced scale, environmental perspective view thereof; and,

FIG. 9 is a rear perspective view of bag in open position thereof.

The broken lines showing a bag is for the purposes of illustrating environment and form no part of the claimed design. The elements of the bag lock are shown detached in the drawing views of FIGS. 8 and 9 for clarity of illustration.
